UNITED STATES PATENT OFFICE.

JOHN C. KRIEG AND FRANK FISHBAUGH, OF NEWARK, OHIO.

COMPOSITION HEEL.

1,331,713.

Specification of Letters Patent. Patented Feb. 24, 1920.

Application filed June 14, 1919. Serial No. 304,104.

To all whom it may concern:

Be it known that we, JOHN C. KRIEG and FRANK FISHBAUGH, citizens of the United States, residing at Newark, in the county of

5 Licking, State of Ohio, have invented a new and useful Composition Heel, of which the following is a specification.

This invention relates to heels, and particularly to composition or rubber heels 10 adapted for attachment to boots, shoes or the like.

The primary object of the invention is to provide a heel of this character having an anti-slipping ground engaging surface 15 whereby the wearer is prevented from slipping while walking on wet or irregular surfaces.

A further object is to provide novel means for facilitating the securing of the heel to 20 the article used in combination therewith.

With the foregoing and other objects in view which will appear in the description, the invention resides in the combination and arrangement of parts and in the details of 25 construction hereinafter claimed, it being understood that changes in the detail embodiment of the invention may be made within the scope of the claim, without departing from the spirit of the invention.

30 A practical embodiment of the invention is disclosed in the drawings in which:—

Figure 1 illustrates in plan the heel as applied to a shoe;

Fig. 2 is a sectional view taken on line 35 2—2 of Fig. 1;

Fig. 3 is a detail view of a metal plate.

Referring in detail to the drawing, the numeral 5 indicates a heel constructed in accordance with our invention the same including 40 a curved shoe engaging surface 6, and a curved ground engaging surface 7, having curved side ribs 8, and transversely curved front and rear ribs 9, the ends of the transversely curved ribs 9 terminating short 45 of the curved side ribs 8 to provide spaces 10 for increasing the efficiency of the rubber heel proper.

As shown by Fig. 1 of the drawings, these ribs 8 and 9 extend beyond the plane of the 50 edge 9' of the heel thus insuring the engagement of the ribs with the ground surface, when in use.

Disposed centrally of the body of the heel 5, and embedded in the composition of the 55 heel, within the area of the ribs 8 and 9, which as shown are arranged to form a rec-

tangular space 11, is an anti-slip plug 12 composed of fibrous material and constructed to present curved front and rear surfaces 14 and 15. While the plug 12 is embedded 60 in the composition forming the body of the heel 5, the same is of a length to extend beyond the surfaces of the ribs 8 and 9, in order that the plug 12, which is of much tougher material than the composition forming 65 the ribs 8 and 9, will receive the initial wear of the heel and at the same time prevent to a degree, slipping of the heel, before the ribs 8 and 9 contact with the surface on which the wearer is walking. 70

From the foregoing it will be seen that due to the arrangement of the ribs 8 and 9, and anti-slip plug 12, a four way non-slip ground engaging surface is provided, the ground engaging surface of the ribs 8 and 9 75 being curved, as shown by the drawing to enable the ribs to adjust themselves to irregular surfaces.

As clearly illustrated, the heel 5 is provided with an opening 15 extending therethrough, said opening being arranged to receive the nail, spike, or other means employed for securing the heel 5 to the shoe or article to which the heel is to be attached. 80

Embedded within the heel 5 and arranged 85 adjacent the opening 15 thereof, is a triangular plate 16, the same being provided with relatively small openings 17 formed in the body portion thereof and adjacent the edges, which openings permit quantities of rubber 90 to enter to cause the plate to become united with the body portion of the rubber heel during the molding process thereof, so that the metallic plate 16 may be secured to the body portion of the heel. 95

Disposed substantially centrally of the plate 16, is an elongated opening 18, which opening, is adapted to register with the opening 15 formed in the heel proper, so that the securing means which passes through the opening may also pass through the elongated opening 18. 100

From the foregoing it is obvious that the structure as shown and described is especially adapted for use in connection with 105 relatively small heels such as Cuban, French, or Common Sense heels, since the same tends to give the heel a rigid form and close adherence to its support.

What we claim is:—

110 A cushion heel provided on its tread surface with two sets of curved ribs extending

respectively longitudinally and transversely thereof, to resist both forward and side slippage, a centrally disposed anti-slip plug extending beyond the plane of the top surfaces of the ribs, and a curved metal plate embedded in the heel and apertured to permit the passage of securing means.

In testimony that we claim the foregoing

as our own, we have hereto affixed our signatures in the presence of two witnesses.

JOHN C. KRIEG.
FRANK FISHBAUGH.
